HYDROCARBON OIL CONVERSION

Donald F. Gerstenberger, Chicago, Ill., assignor
to Universal Oil Products Company, Chicago,
Ill., a corporation of South Dakota

Application April 4, 1932. Serial No. 602,904

3 Claims. (Cl. 196—60)

This invention relates to the conversion of hydrocarbon oil, and more particularly refers to improvements in the type of cracking process and apparatus wherein the hydrocarbon oil is subjected to conversion conditions of elevated temperature and substantial superatmospheric pressure in a heating element, followed by continued conversion, at superatmospheric pressure, particularly of the vaporous materials resulting from the heat treatment, quick separation of residual liquid from the vapors and further vaporization of the latter at reduced pressure.

The improvements of the present invention are particularly concerned with the quick separation from the vapors and removal from the reaction zone of residual liquid conversion products during the conversion time in the reaction zone following the heating element and comprise methods and means of removing said residual liquid products at various stages during this continued conversion time instead of removing the total residual liquid products together with the vapors from the reaction zone. In this manner the residual liquid is subjected to much shorter conversion time than the vapors. The advantages of short liquid conversion time and prolonged vapor conversion time are sufficiently well known to require no explanation or justification here.

One specific manner in which the advantages of the concepts of the present invention may be obtained comprises utilizing a plurality of elongated vertical reaction chambers connected in series, heated conversion products from the heating element of the system entering the upper portion of the first reaction chamber, vapors from the lower portion of each chamber passing to the upper portion of the succeeding chamber and residual liquid being withdrawn from the lower portion of each chamber. In the last chamber of the series the residual liquid formed in this zone may be withdrawn therefrom separately or together with the final vaporous product from the entire series and, in the preferred embodiment of the invention, both vaporous and liquid products from the reaction zone are discharged into a reduced pressure vaporizing chamber although, when desired, the vaporous products may pass from the reaction zone directly to fractionation while the residual liquids removed from each reaction chamber are commingled and subjected to further vaporization at reduced pressure. In the arrangement above described, any number of a plurality of reaction chambers may be employed, their diameter and height being

preferably so proportioned to give substantially the same total vapor time that would be obtained in the ordinary type of single vapor-phase reaction chamber but giving an increased vapor velocity. High vapor velocity alone has been known to decrease the deposition of coke and, as here used, in combination with the quick removal of coke-forming residual liquids at various stages during the treatment, will, under the proper temperature and pressure conditions for the particular oil being treated, substantially eliminate coke deposition in the reaction zone and in many cases will even permit the use of an increased conversion temperature without increasing the coke and gas formation, thereby materially improving the anti-knock value of the finished motor fuel product of the system.

The attached diagrammatic drawing illustrates one specific form of apparatus incorporating the features of the present invention and in which the process of the invention may be successfully practiced. Raw oil charging stock may be supplied through line 1 and valve 2 to pump 3 from which it may be fed through line 4 and valve 5 to heating element 6. When desired, a portion or all of the raw oil may pass from pump 3 through line 7 and valve 8 into fractionator 9 wherein it comes into direct and countercurrent contact with the cracked vapors, serving to partially cool the latter and assist their fractionation and being thereby preheated. The relatively heavy components of the vapors are condensed in the fractionator and collect, together with the preheated raw oil, in the lower portion thereof, from which they are withdrawn through line 10 and valve 11 to pump 12. The reflux condensate or reflux condensate and preheated raw oil from fractionator 9 is directed from pump 12 through line 13 and valve 14 into line 4, commingling therein with the raw oil, or that portion, if any, supplied directly to line 4 from pump 3, and passing therewith to heating element 6.

Heating element 6 is located in a furnace of any desired form suitable for supplying the required heat to the oil undergoing conversion. The heated oil is discharged from heating element 6 through line 16 and valve 17 into the upper portion of reaction chamber 18.

Chambers 18, 19 and 20 are similar reaction zones wherein conversion of the vaporous products may continue for a predetermined time while the residual liquid products are removed therefrom without being subjected to extensive further conversion time. Products from heating element 110

6 pass downward through chamber 18. The unvaporized liquid which enters this zone and the residual liquid formed during passage of the materials through this chamber are withdrawn from its lower portion through line 21 and valve 22. Vaporous products separately withdrawn from chamber 18 pass through line 23 into the upper portion of chamber 19, passing downward through this zone. The residual liquid formed in chamber 19 is withdrawn from its lower portion through line 24 and valve 25 while the vaporous products are separately withdrawn through line 26 and enter the upper portion of chamber 20, passing downward therethrough. The residual liquid formed in chamber 20 is withdrawn from its lower portion through line 27 and valve 28. The vapors from chamber 20, which comprise the total conversion products remaining in vaporous form at this state of the process, may be handled in any one or any combination of several manners. They may be separately withdrawn from the lower portion of chamber 20 through line 29 and may pass through line 30 and valve 31 directly to fractionator 9, or they may be directed, all or in part, through valve 32, in line 29, into line 33 and thence to reduced pressure vaporizing chamber 35 or, when desired, all or any portion of the vapors may be withdrawn from chamber 20, together with the residual liquid formed in this zone, through line 27 and valve 28. The residual liquids from each of the chambers are commingled in line 33 and pass through valve 34 into reduced pressure vaporizing chamber 35. In case all or any portion of the vapors from chamber 20 pass either through line 27 and valve 28 or through line 29 and valve 32 into line 33, they commingle therein with the residual liquid products and pass therewith to chamber 35, serving to further heat these products and assist their vaporization at reduced pressure.

Residual liquid remaining unvaporized in chamber 35 may be withdrawn therefrom through line 36 and valve 37 to cooling and storage or to any desired further treatment. Vapors from chamber 35 pass through line 38 and valve 39 into fractionator 9 which, in the case illustrated, is the same fractionator to which vaporous products from chamber 20 are directed, in case they are not first commingled with the residual liquid.

The heavy components of the vapors supplied to fractionator 9 are condensed by fractionation in this zone, passing therefrom, as already described, to heating element 6 for further conversion. The light components of the vapors remaining uncondensed within the fractionator are withdrawn from the upper portion thereof through line 40 and valve 41, are subjected to condensation and cooling in condenser 42, distillate and uncondensable gas from which are directed through line 43 and valve 44 to collection in receiver 45. Uncondensable gas may be released from receiver 45 through line 46 and valve 47. Distillate may be withdrawn from the receiver through line 48 and valve 49. A portion of the distillate from receiver 45 may, when desired, be recirculated to the upper portion of fractionator 9 by well known means (not shown), to assist fractionation of the vapors in this zone and control the vapor outlet temperature.

A substantial superatmospheric pressure of the order of 100 to 500 pounds, or more, per square inch, is preferably employed in the heating element and in the reaction chambers. Substan-

tially reduced pressure of the order of 100 pounds down to substantially atmospheric may be employed in the vaporizing chamber and the pressure in the succeeding fractionating, condensing and collecting portions of the cracking system 80 may be substantially equalized therewith. The conversion temperature employed at the outlet from the heating element may range, for example, from 850 to 1,000° F.

The following examples of specific operating 85 conditions and results obtainable by their use are given for the purpose of more clearly illustrating the features and advantages of the present invention. Let us first consider a cracking operation such as that above illustrated and described except that only one high pressure reaction chamber is employed, products from the heating element entering its upper portion while both vaporous and liquid products are simultaneously withdrawn from the lower portion of the 90 chamber and directed to the reduced pressure vaporizing chamber. The raw oil charging stock supplied to this system is a blend of Pennsylvania naphtha and fuel oil having a gravity of approximately 43° A. P. I. A temperature of about 925° 100 F. is employed at the outlet from the heating element and a pressure of about 350 pounds is utilized in the heating element and reaction chamber. The pressure in the vaporizing chamber is reduced to approximately 50 pounds per square 105 inch. This operation may yield, per barrel of charging stock, about 80% of motor fuel having an octane number of approximately 73 and about 6% of heavy residual oil having a gravity of about 4° A. P. I. The gas production is less than 400 110 cubic feet per barrel of charging stock, but the total coke, gas and loss is approximately 14%.

In another operation utilizing the same charging stock and the same type of operation, with the exception that the features of the present 115 invention are utilized by employing three reaction chambers such as illustrated and above described; the reaction chambers are substantially the same length as the single reaction chamber utilized in the above operation and the cross-sectional area of each is approximately one-third of that of the single reaction chamber, thus giving substantially the same vapor reaction time and about three times the vapor velocity through the reaction zone. In this operation the temperature 120 of the oil leaving the heating element is increased to approximately 935° F. The yield of gasoline recovered by this operation is substantially the same (approximately 80% of the charging stock) and its anti-knock value is increased to an octane 125 number of approximately 78. About 10% of residual oil of improved quality may be recovered and the production of gas is slightly increased but, owing to the decreased formation of coke in the reaction zone and the negligible deposition of this material in the reaction chambers, the operating time is greatly prolonged over that possible in the first operation described.

I claim as my invention:

1. A hydrocarbon oil cracking process which 140 comprises heating the oil to cracking temperature under pressure while flowing in a restricted stream through a heating zone, discharging the heated oil into the upper portion of an unheated vertically elongated reaction zone maintained under cracking conditions of temperature and pressure, passing the vapors and unvaporized oil 145 downwardly through the reaction zone and separately removing the vapors and unvaporized oil from the lower portion of the reaction zone, in- 150

- introducing the vapors to the upper portion of a second vertically elongated reaction zone maintained under cracking conditions of temperature and pressure, passing the vapors downwardly through the second reaction zone and removing the same from the lower portion thereof, passing the unvaporized oil withdrawn from the first-mentioned reaction zone and such liquid constituents as are formed in the second reaction zone to a vaporizing zone maintained under lower pressure than the reaction zones and distilling the same therein, supplying the vapors evolved in the vaporizing zone and the vapors withdrawn from the second reaction zone to a common fractionating zone and fractionating the admixed vapors therein, returning resultant reflux condensate to the heating zone for recycling through the process, and finally condensing the fractionated vapors. 80
2. A hydrocarbon oil cracking process which comprises heating the oil to cracking temperature under pressure while flowing in a restricted stream through a heating zone, discharging the heated oil into the upper portion of an unheated vertically elongated reaction zone maintained under cracking conditions of temperature and pressure, passing the vapors and unvaporized oil downwardly through the reaction zone and separately removing the vapors and unvaporized oil from the lower portion of the reaction zone, introducing the vapors to the upper portion of a second vertically elongated reaction zone maintained under cracking conditions of temperature and pressure, passing the vapors downwardly through the second reaction zone and removing the same from the lower portion thereof, subsequently combining the vapors with the unvaporized oil withdrawn from the first-mentioned reaction zone and introducing the resultant mixture into a vaporizing zone maintained under lower pressure than the first-mentioned reaction zone, separating the mixture into vapors and residue in the vaporizing zone, fractionating the last-mentioned vapors to condense heavier fractions thereof and returning resultant reflux condensate to the heating zone, and finally condensing the fractionated vapors. 85
3. In a hydrocarbon oil cracking process of the character wherein the oil is heated to cracking temperature under pressure while flowing in a restricted stream through a heating zone, the vaporous and liquid oil thence passed downwardly through an unheated vertically elongated reaction zone, the liquid oil withdrawn from the lower portion of the reaction zone and flash distilled in a vaporizing zone by pressure reduction; the improvement which comprises separately removing vapors from the lower portion of the reaction zone and passing the same through a series of vertical vapor reaction zones maintained under cracking conditions of temperature and pressure, introducing the vapors to the upper portion of each of the vapor reaction zones to flow downwardly therethrough and removing the vapors from the lower portion of each of the vapor reaction zones, introducing liquid constituents formed in the vapor reaction zones to said vaporizing zone, combining the vapors withdrawn from the last vapor reaction zone of the series with the vapors evolved in the vaporizing zone, fractionating the vapor mixture to condense heavier fractions thereof and returning resultant reflux condensate to the heating zone, and finally condensing the fractionated vapors. 90
